DESIGN FOR A GLASS CUTTER

Guy C. Wyman, Chatham, N. J., assignor to Landon P. Smith, Incorporated, Irvington, N. J., a corporation of New Jersey

Application September 7, 1937, Serial No. 71,499

Term of patent 14 years

To all whom it may concern:

Be it known that I, Guy C. Wyman, a citizen of the United States, residing at Chatham, in the county of Morris and State of New Jersey, have invented a new, original, and ornamental Design for a Glass Cutter, of which the following is a specification, reference being had to the accompanying drawing, forming part thereof.

Fig. 1 is a side elevational view of the glass cutter showing my new design; and

Fig. 2 is a plan view of the cutter shown in Fig. 1.

I claim:

The ornamental design for a glass cutter, as shown.

GUY C. WYMAN.
